DESIGN FOR A HOBBYHORSE

William Francis Pogue, Spokane, Wash.

Application October 28, 1939, Serial No. 87,915

Term of patent 3½ years

To all whom it may concern:

Be it known that I, William Francis Pogue, a citizen of the United States and a resident of Spokane, in the county of Spokane, and State of Washington, have invented a new, original, and ornamental Design for Hobbyhorses, of which the following is a specification, reference being had to the accompanying drawing, forming part thereof.

Fig. 1 is a side perspective view of a hobbyhorse, showing my new design; and

Fig. 2 is a bottom plan view thereof.

I claim:

The ornamental design for a hobbyhorse, as shown.

WILLIAM FRANCIS POGUE.
